UNITED STATES PATENT OFFICE.

WILLIAM EARL SNAPP, OF NATOMA, KANSAS.

SLIDING-DOOR LOCK.

1,173,884.

Specification of Letters Patent. Patented Feb. 29, 1916.

Application filed September 25, 1915. Serial No. 52,678.

To all whom it may concern:

Be it known that I, WILLIAM EARL SNAPP, a citizen of the United States, residing at Natoma, in the county of Osborne and State 5 of Kansas, have invented new and useful Improvements in Sliding-Door Locks, of which the following is a specification.

The present invention relates to new and useful improvements in locks for sliding 10 doors.

An object of the invention is to provide an extremely simple and effective lock which, when placed on a sliding door will securely lock the same, the keeper passing 15 within the lock to prevent access thereto, thereby preventing it from being unlocked except by the use of the proper key.

With the above and other objects in view, the improvement resides in the construction, 20 combination and arrangement of parts set forth in the following specification and falling within the scope of the appended claims.

In the drawing: Figure 1 is a view illustrating the application of the improvement, 25 Fig. 2 is a sectional view approximately on the line 2—2 of Fig. 1, and Fig. 3 is a sectional view on the line 3—3 of Fig. 2.

While the improved lock is primarily designed for employment upon the sliding 30 doors of freight cars, it is to be understood that the same may be employed with equal efficiency in other connections, as for instance, upon the sliding doors of passenger cars, mills, factories, etc., and in the accompanying drawing, the numeral 1 designates a sliding member and 2 a stationary member.

In the illustrative embodiment of the drawings, the stationary member 2 has secured thereto a keeper member 3, the same having its end projecting inwardly of the door opening, and this end is formed with a hooked nose 4.

The main body of the casing of the improved lock may be let into a suitable mortise in the end of the door which abuts with the stationary member 2 and the outer or cover plate of the casing is provided with lugs or extending portions which project 50 over the casing and which has suitable covering plate, for the reception of securing elements, the said securing elements lying flush with the said covering plate. The lock casing preferably comprises a substantially rectangular member having its edges

flanged, and the lower flange formed with an angular extension 6 which terminates in a straight wall 7. The extension 6 is arranged opposite the opening 8 through which the keeper is adapted to pass and the sliding member 1 is brought into contact with the stationary member 2. The straight wall 7 of the extension 6 is adapted to serve as an abutment or stop member for the central or body portion 9 of a latch 10, the said latch being recessed to receive the straight wall and the rear angular wall of the said extension. The latch has its rear end formed with an opening through which passes a pivot stud 11, and also secured to the said rear wall is one end of a spring 12, the opposite ends of said spring being connected with the rear flange of the casing, as at 13, and the said spring is adapted to swing the latch upon its pivot 11 to bring the same 70 into contact with the extension 6 and the straight wall 7 thereof. The opposite or outer end of the pivoted latch may contact with the inner wall of the outer flange of the casing and the same is provided with a downwardly extending rounded hook or 75 nose 14 which is disposed opposite the opening 8 so that when the movable member 1 is brought into contact with the stationary member 2 the hooked nose 4 of the staple 80 contacting with the outer rounded surface of the nose 14 of the pivoted latch will swing the said latch until the straight portion of the hook 4 engages with the straight wall of the hook or nose 14 of the latch. 90

The pivoted latch 10 opposite the recessed portion thereof which rests upon the straight wall 7 of the extension 6 is formed upon its opposite side with depressions 15, the front walls of which being substantially straight 95 and the rear walls curved, as indicated by the numeral 16. Pivoted within these depressions is the bifurcated curved end 17 of a tumbler 18. The upper or opposite end of the tumbler is formed with a head 19 which 100 has a plurality of kerfs 20 adapted to be received in the wards of a suitable key, and the weighted headed end of the tumbler is adapted to swing the same against the curved walls of the depressions to retain 105 the tumbler in proper position to be engaged by the bit of the key and will when disengaged by the key return to its initial position. When the tumbler is forced upwardly by the key the pivoted latch will have 110

its nosed end swung to bring the same out of engagement with the hooked end of the keeper to permit of the opening of the door.

From the above description, taken in connection with the accompanying drawing, the simplicity of the device, as well as the advantages thereof will, it is thought, be perfectly apparent to those skilled in the art to which such invention appertains without further detailed description.

Having thus described the invention, what I claim is:

1. A bolt having one of its ends pivoted to the lock casing, said casing having an extension providing a stop for the said latch, a spring for swinging the latch against the stop, said latch having one of its ends abutting with one of the flanged walls of the casing at the opening thereof, the said end being formed with a downwardly extending hooked nose, the outer face of which being rounded, a gravity pawl pivoted to the latch, said pawl having an offset head which is kerfed, and the said head being arranged adjacent the key opening in the casing.

2. A movable element and a stationary element providing an abutment for the movable element, a hooked staple upon one of the elements and projecting over the other element, said casing having its edges flanged

and one of its said flanges cut to provide an opening for the hooked end of the keeper, the lower horizontal flange having an angular extension terminating in a horizontally straight surface, a latch pivoted at one end within the casing, said latch having its lower face formed with a depression to engage with the extension of the casing, spring means for forcing the latch in such contact, the outer end of the latch contacting with the outer flange of the casing above the opening therein, and the latch being provided at the said end with a downwardly extending hooked nose to engage with the hook of the keeper, the body of the latch, at the upper edge thereof having its opposite sides depressed and the rear walls of said depression being rounded, a tumbler having a curved bifurcated end and pivotally secured in the depressions, said tumbler having its opposite end formed with an offset head which is kerfed and which is arranged in proximity to the latch opening of the casing.

In testimony whereof I affix my signature in presence of two witnesses.

WILLIAM EARL SNAPP.
